CLOTHES WRINGER

William F. Peters and David L. Todd,
Dayton, Ohio

Application March 13, 1934, Serial No. 715,307

2 Claims. (Cl. 68—32)

This invention relates to new and useful improvements in clothes wringers.

It is one of the principal objects of our invention to provide means for conveying the wet clothes between the wringer rolls to prevent accidental injury to the fingers when placing said clothes directly between the revolving rolls.

It is another object of the invention to provide means for preventing adhesion of the clothes to the wringer rolls after passing between them.

It is still another object of our invention to provide conveyor means to convey the clothes away from the rolls after passing between them.

Other important and incidental objects of the invention will be set forth in the following specification and more particularly described in the subjoined claims.

In the accompanying drawing illustrating our invention, Figure 1 is a cross sectional view taken through the wringer. Figure 2 is an end view of the same, partly in section and showing the roller mounting. And Figure 3 is a sectional view taken on the line 3—3 of Figure 1.

Referring now to the drawing for a detail description of our invention, the numeral 1 designates a wringer having opposite channel end frames 2 and 3 joined at their lower ends by a transverse member 4 and at their upper ends by an inverted channel cap 5.

Secured between the flanges of each one of the channel members 2 and 3, and above the lower member 4, are fixed bearings 6 and 7 respectively.

In these bearings there are journalled the axial extensions 8 and 9 of a lower wringer roll 10 that is covered with a yieldable material such as rubber. Beyond the bearing 6 I have provided in the end frame 2 an aperture through which the axial extension 8 projects, to receive upon it, outside of the frame 2, a gear 11 and a driving connection 12. The latter may be either a crank for hand operation, or the conventional power drive.

Above the bearings 6 and 7, and slidably positioned between the flanges of the end frames 2 and 3, are bearings 13 and 14 for an upper yieldably mounted pressure roll 15. This roll is positioned in tangential relation with the lower roll 10, with which it co-acts and against which it is forced by the following means.

Attached to the top of each bearing 13 and 14 and extending transversely of the wringer, between them, is an arched flat spring 16. Positioned above this spring and to which it is at-

tached at its center, is another inverted arched flat spring 17.

The outer ends of the spring 17, between the flanges of the end frames 2 and 3, are received between the depending forked ends 18 of a yoked pressure member 19 that extends transversely of the wringer beneath the cap 5.

In the center of the cap 5 I have provided a pressure adjusting screw 20 whose lower end engages the pressure member 19 beneath the cap 10 to regulate the pressure between the rollers 10 and 15.

Above the spring 17 I have positioned a flanged idler roller 21 whose axial extensions 22—22 are journalled in bearings 23, 23. These bearings are attached to the up-turned ends of oppositely disposed flat spring members 24, 24, secured to the spring 17, that force the roller 21 upwardly.

Surrounding the roller 21 and the wringer roller 15 is an endless belt 25 equal in width to the length 20 of the wringer rolls and maintained taut by the force of the springs 24, 24.

Beyond the bearing 13, the axial extension of the roller 15 projects through an elongated hole 26 in the end frame 2, to permit the vertical 25 movement of the roller 15 when material passes between the rolls. Secured to the end of this axial extension, beyond the end frame 2, is a gear 27 similar to the gear 11 with which it mates. Covering the gears 11 and 27 is a flanged housing 30 secured to the end frame, and providing mounting means for the wringer 1.

On each side of the wringer 1 I have provided an outwardly sloping bracket member 29, formed at each side thereof with downwardly turned side 35 flanges 30, 30. At their inner ends these flanges 30, 30 are bent outwardly for attachment to the flanges of the end frames 2 and 3. At the outer ends of the bracket members 29, 29, there is freely mounted between the projecting ends of their 40 side flanges 30, 30, flanged rollers 30a, 30a.

Passing under the wringer, over the opposite rollers 30a, 30a, and the bracket members 29, 29, and between the rollers 10 and 15, is an endless conveyor belt 31 of fabric such as rubberized 45 canvas or the like.

Now, when the wringer rollers 10 and 15 are rotated, the endless conveyor belt 31 will carry the wet clothes deposited upon it above the bracket member 29, between these rollers, being partly 50 guided by marginal flanges 32, 32 attached to the sides of each bracket member 29.

When the wet clothes pass through these rollers, they will be deflected from the upper roller 15 by the upper endless belt 25, and again deposited 55

upon the receding portion of the conveyor belt 31.

Upon reaching the roller 30^a, these clothes which have been passed through the wringer rolls will be discharged from the wringer conveyor belt.

5 From the foregoing description it will be seen that our invention is a distinct improvement in clothes wringers, since all the hazards incident to feeding the wet clothes directly between the revolving wringer rolls are eliminated. Furthermore, the provision of the upper endless belt 25 renders impossible the wrapping of the clothes about the upper roller, thus not only protecting delicate fabrics from injury but avoiding delays or damage to the driving mechanism due to the 10 clogging of the rolls.

15 It is also evident that with our conveyor means, clothes may be removed from very hot water by tongs or other suitable means and deposited on the conveyor belt without subjecting the hands 20 to injury in the hot water.

25 While we have shown our conveyor belt and non-wrapping features as an integral part of a wringer, it is evident that these means can easily be attached to an existing wringer as an improvement.

Having described our invention, we claim:

1. In a clothes wringer of the type described, spaced end frame members, a lower pressure roller journalled between said end frame members, a second pressure roller journalled between 30 said end frame members, oppositely disposed, con-

nected arched flat springs between the end frame members, a bracket member projecting outwardly from each side of said end frame members, an endless conveyor belt passing around said bracket members and between said pressure rollers, and a second endless belt passing between said pressure rollers and above said springs to prevent the clothes from wrapping around said second rollers. 5

2. In a clothes wringer of the type described, 10 spaced end frame members, a lower pressure roller journalled between said frame members, bearings slidably mounted in the latter, above the lower pressure roll, a second pressure roller carried by said bearings, an arched, flat spring 15 attached at its ends to the tops of said bearings and extending transversely of the wringer, an inverted arched, flat spring attached at its center to the first spring, a yoked pressure member to which the ends of the second spring are attached, 20 means engaging said pressure member from above to adjust its tension, a bracket member projecting outwardly from each side of said end frame members, an endless conveyor belt passing around said bracket members and between said pressure 25 rollers, and a second endless belt passing between said pressure rollers and above and around said flat springs to prevent the clothes from wrapping around the second roller.
